United States Patent Office

Des. 191,128
Patented Aug. 15, 1961

191,128

LIGHT FIXTURE

Paul J. Curtin, South Milwaukee, Wis., and Edward B. Smith, Jr., Arlington Heights, and Raoul E. Rodriguez, Chicago, Ill., assignors to McGraw-Edison Company, Milwaukee, Wis., a corporation of Delaware

Filed Sept. 8, 1960, Ser. No. 62,061

Term of patent 14 years

(Cl. D48—31)

FIG. 1 is a front elevation of a light fixture embodying our new design;

FIG. 2 is a top plan view thereof; and

FIG. 3 is a bottom plan view taken along lines 3—3 of FIG. 1.

The dominant features of our design reside in the portions shown in full lines.

We claim:

The ornamental design for a light fixture, as shown and described.
